UNITED STATES PATENT OFFICE.

FRANCIS H. RICHARDS, OF HARTFORD, CONNECTICUT.

SEWING-MACHINE.

1,191,232.

Specification of Letters Patent. Patented July 18, 1916.

Application filed January 24, 1901, Serial No. 44,547. Renewed February 14, 1916. Serial No. 78,327.

To all whom it may concern:

Be it known that I, FRANCIS H. RICHARDS, a citizen of the United States, residing at Hartford, in the county of Hartford and 5 State of Connecticut, have invented certain new and useful Improvements in Sewing-Machines, of which the following is a specification.

This invention relates to sewing machines, 10 and especially to the parts thereof which form the stitches and control the fabric; and its principal object is to improve the construction and operation of the machine, with a special view to facilitating its manipulation, 15 as well as the insertion, adjustment and removal of the fabric. I show an improved organization, whereby the necessity of stopping the machine when it is desired to stop the stitch-forming and fabric-feeding opera- 20 tions, is avoided. In this instance, the needle upon being thrown off preferably continues to reciprocate, but does not descend far enough to coöperate with the looper; and its stroke when thrown off is 25 preferably shorter than when operative.

According to my present improvements, a 30 needle slide is operated by a link motion, the position and effective relation of whose several members may be varied at will, so that the power-shaft of the machine may communicate through said link motion to the needle either a full, low working stroke or a short 35 high idle stroke, as desired. Preferably the presser foot is also thrown off by the same finger piece that throws the needle out of 40 operation, thereby stopping both the stitch-forming and fabric-feeding operation while the machine is running.

In the accompanying drawings, Figure 1 45 is a side elevation of a sewing machine embodying one form of my invention. Fig. 2 is an end elevation of the sewing machine head and its appurtenances, a portion of the cover plate thereof being broken away, and 50 the needle and presser being shown in their operative or effective positions. Fig. 3 is a view similar to Fig. 2, but showing the needle and presser thrown off. Fig. 4 is a vertical section on the line *a—a* of Fig. 2. Fig. 5 is a horizontal section on the line 55 *b—b* of Fig. 2; and Fig. 6 is a perspective of a vertical presser bar, which also serves as a guide for a needle slide.

Similar characters designate like parts in the several figures of the drawings. 55

The sewing machine may consist generally of a bed plate B, an upright and arm A, carrying a head H, a shuttle or looper S, a needle N, and actuating mechanism D. Preferably the needle is formed integral 60 with a large thin sheet-metal slide 10, guided at its edges in ways 11 and 12 formed in a vertical presser bar 13. The latter is provided with guiding ribs 14, working in grooves 15 formed in the machine head, 65 which is hollow or box-like and preferably provided with a lid 16 depending from a hinge 17 and closed by a thumb screw 16'. Said lid retains in their seats both the presser and the needle slide, whose outer 70 faces are flush with the edge of the rim of the box-like head. A foot 13^a is secured to a lug 13^b upon said presser 13 by means of a screw 13^c.

Through the arm A of the machine frame 75 extends a horizontal needle-actuating rock-shaft D' suitably connected to the lower driving shaft of the machine; said rock shaft carrying within the machine head H a crank 18, the latter being connected by a 80 linkage or link-system or train with the needle slide 10. Said linkage consists of an upper link 19 and a lower link 20, the upper link being articulated at its upper end to the crank 18, and the lower end of the lower 85 link having a stud 21 fitting in a socket in the needle slide, and said links being joined at 19' during the full operation of the machine, said connected or toggle-links 19 and 20 act somewhat in the manner of a single 90 link, to transmit the movement of the crank 18 to the needle slide, thereby reciprocating the latter in its ways. The presser is recessed or grooved at 22 to afford a clearance for the lower portion of the link 20. 95

The device for throwing the needle out of operation which may be called a throw off device includes a horizontal spindle 24 mounted in a boss 23 on the machine head and having upon its inner end a crank 25, 100 the latter being connected by a transverse link 26 to the needle-driving train 19, 20 so as to control the latter. The link 26 is preferably articulated to the pivot 19' in said train. When the crank 25 is swung, the 105 train or toggle is caused to buckle, thereby

altering the relation of the driving crank 18 to the needle slide 10, as at Fig. 3. Said throw-off crank 25 is also connected by a downwardly extending link 27 to a lug 28 on the presser bar, the upper end of this link having a slot 29 engaging a shoulder-screw or pin 30 upon said crank, thereby making a loose connection between the crank and presser, so that when the latter is lifted by the fabric it may not affect the crank and cause it to interfere with or vary the movements of the needle-drivers. From the lug 28 also depends a rod 31, extending through horizontal walls or flanges 32 and 33 of the machine head; and upon the lower end of the rod may be threaded an adjustment sleeve 34, against which may bear the lower end of a compression spring 35, the latter coiling about said rod and bearing at its upper end against the flange 32, and pressing the foot 13^a upon the cloth plate or the fabric thereon.

The crank spindle 24 is intended for manual adjustment, and for this purpose 25 may be provided with a lever or knurled head 36; and the range of movement of the crank 25 may be determined by stops 37 and 38 fixed upon the machine head.

When the mechanism is set in the position 30 shown at Fig. 2, the links 19 and 20 are nearly in line during the entire needle movement, thereby imparting a full stroke to the needle, carrying it down sufficiently to enable it to coöperate with the shuttle, as shown in 35 full lines, the position of the parts at the top of the needle stroke being shown in dotted lines. The upper end of the slot 29 in the presser bar link 27 preferably just contacts with the pin 30, the slight upward 40 movement of the presser foot due to the rising of the feed-dog not producing any effect upon the needle-controlling devices.

In order to stop the stitching and feeding operations while the machine is running, 45 the finger piece 36 is turned so as to swing the crank 25 upwardly and forwardly until it contacts with the stop 38. The crank is held yieldingly in this position by the spring 35, which is compressed at the said adjustment 50 of the crank, acting through the presser link 27, which passes over the dead center of the axis 24 as the crank swings forward. During said movement of the crank, the link 26 is thrust forwardly, buckling the toggle 19, 20 so that movement is 55 no longer communicated in a direct line from the crank 18 to the needle, but instead the upper link 19 is brought nearly at right angles to the lower link 20, so that the vibrations 60 of the crank arm effect through the former idle vibrations of the latter and slight vertical movements of the needle slide 10, as indicated by full and dotted lines at Fig. 3. One effect of the described throw-off movement, arising from the buckling of 65

the toggle 19, 20, is to draw up the needle slide 10, so that it works above its normal range of action; and so long as this result is effected, it is not essential in all cases that the stroke of the needle when thrown off be 70 shorter than when it is in full operation. It will be seen that by this means the stitch-forming and work-feeding operations may be stopped and subsequently resumed while the machine is running.

It will be seen that the withdrawal of the needle from the work with the presser-foot makes it possible to stop the stitching and feeding operations of the machine while the driving mechanism continues in operation 80 without any danger of tangling the thread, and the shortening of the needle stroke permits the construction of the parts with a minimum projection of the needle beyond its guides, thereby reducing the lateral variation in the position of the needle which would be caused by any given amount of play in the fitting of the parts.

As a convenient means for operating the needle-actuating rocker-shaft D', and for 90 properly operating the reciprocating shuttle in proper timing with the needle, I have illustrated a driving mechanism, herein-before designated in a general way by D, and which, in the form herein shown, comprises a driving-shaft 39 mounted in bearings 40 and 41 formed on or secured to the frame work of the machine, which shaft 39 carries an eccentric 42 connecting through a rod 43 with an arm 44 of said needle-actuating shaft D'. Said primary driving-shaft 39 is also shown provided with a cam 45 that connects with the short end 46 of a shuttle actuating-lever 47, said lever being shown pivoted to the frame work of the machine at 48. It will, however, be understood that other suitable mechanism may be employed in connection with my present improvements in the machine herein illustrated.

It will be observed that the vibratory link-controlling arm 26 is pivoted upon the throw-off arm 25, whereby it may be shifted bodily, as from the position at Fig. 2 to that at Fig. 3, so as to vary the needle stroke, or throw the needle into or out of operation; that the actuator 18 is connected by a link 19 to the train of devices 26, 20, preferably to the latter; that the link motion which controls the needle comprises the members 18, 19, 20, 25 and 26; that the arm 26 extends transversely of the link 20, so that said arm may vibrate while the needle is operated by said link, and also so that said arm may by a longitudinal movement thrust 120 said link out of effective position, as at Fig. 3; that the members 19 and 20 may be regarded as a toggle, whose effective stroke upon the needle slide is controlled by the arm 26; and that the spring 35 holds the 125

arm or crank 25 against the stop 38 when the presser is lifted, as at Fig. 3, thereby yieldingly detaining the links 19, 20 in their altered relation.

5 Variations may be resorted to within the scope of my invention; and portions of my improvements may be used without others.

Certain features herein illustrated are set forth in my simultaneously filed applications Nos. 44,546 and 44,549, and in my other pending applications Nos. 715,282, 10 33,679, 33,680, and 86,673.

Having thus described my invention, I claim—

15 1. A stitch forming mechanism comprising the combination with a presser, a needle slide and a rock arm, of a series of pivoted links connecting the said rock arm and needle slide operatively reciprocating the 20 needle slide when in a comparatively straight line, and a throw off device connected to said series of links and to the presser for bending the line of the links and raising the presser.

25 2. In a sewing machine mechanism, the combination with a reciprocating needle and a presser, of a rock-arm, a needle slide, a pair of links pivoted together and to said arm and slide respectively and effective when 30 said arm is at the limit of its stroke and the links are substantially in alinement for advancing the slide to the limit of its stroke, means for rendering the presser ineffectual, and means controlled thereby for deflecting 35 the alinement of the links so that when the arm is at the said limit of its stroke the needle slide will be in a position short of its limit of stroke.

3. In a sewing machine mechanism, the 40 combination with a reciprocating needle and a presser, of a rock arm, a needle slide carrying the needle, a pair of links connecting said slide and arm and of sufficient length when occupying a position substantially in alinement 45 to advance the slide to its lowest position when the arm is at its lowest position, means connected with the presser for shifting the same to an inoperative position, and means controlled by the shifting means for 50 adjusting the links out of alinement for shortening the throw of the arm and controlling the limit of the down stroke.

4. The combination with a needle and means for actuating the same and comprising 55 a movable member and a system of links connecting the two, of a presser, means for shifting the presser to an inoperative position and connected to said system of links for rendering the needle inoperative.

60 5. The combination with a driver, of a reciprocating needle, a link pivoted to the driver, and a link pivotally connected to the needle, said links being pivoted together, a shifting device connected to said links adja- 65 cent to their interpivotal point, a presser,

and means for moving the presser and operatively connected to said shifting device.

6. A stitch forming mechanism comprising the combination with a presser, a needle and a driver, of links connecting the driver 70 and needle, a throw off device including a crank portion, a link pivoted to said crank portion and to said connecting links, and a link pivoted to said crank portion and to the presser whereby when the presser is raised 75 to an inoperative position the needle is rendered inoperative on the work.

7. The combination with a driver, a presser and a needle, of a link connection between the driver and needle, a device provided with a crank portion, and links joining said crank portion to said connection and to the presser, the latter link having a slot-and-pin connection with one of its co-acting elements. 80

8. The combination with a needle slide of a rock arm, a pair of links pivoted to said arm and slide and pivoted together and when in a substantially straight line capable of advancing said slide to its lowest position 90 upon the arm arriving at its lowest position, a presser foot, a rock arm for raising the said presser foot and a link connecting said rock arm and said pair of links for deflecting these from a straight line upon the raising of the presser foot. 95

9. A stitch-forming mechanism comprising the combination, with a slide, of a presser-foot carried thereby; a needle moving upon the slide; means for actuating said needle; a connection between the actuating means and needle; and a shifting device joined by links to said connection and to the presser. 100

10. In a sewing machine having a presser, a stitch-forming mechanism including a needle slide of a link motion consisting of five elements, namely: a link, as 20, attached to the needle slide, for driving the latter endwise; a controlling arm or link, as 26, attached to said link whereby when the presser is raised to an inoperative position the needle is rendered inoperative on the work; an adjustable arm, as 25, to which said controlling arm is pivoted; an actuating arm or crank, as 18; and a link, as 19, for driving the controlling arm, the link 20, and the needle slide; the link 19 being connected to the crank 18. 110

11. In a sewing machine, the combination with a needle and means for reciprocating the same and comprising a linkage whereby said needle is reciprocated and given a working stroke when the links are in substantial alinement and a shorter stroke when the links are placed out of alinement, a presser, means for controlling the presser, and means connected therewith for shifting the links into and out of alinement so as to alter the limits of the path of the stroke of the needle. 125 180

12. A stitch-forming mechanism of a sewing machine, including a needle-and-presser-mechanism which comprises a stitch-forming mechanism including the combination with a needle device of a link connected thereto; a vibratory controlling arm to which the other end of said link is connected; means for shifting said controlling arm bodily; an actuator connected by a link 10 to one of said link and controlling arm elements; and a presser connected to said shifting means whereby when the presser is raised to an inoperative position the needle is rendered inoperative on the work.
13. A stitch-forming mechanism of a sewing machine, including a needle-and-presser-mechanism which comprises a stitch-forming mechanism including the combination of a needle slide; a link attached thereto; a controlling arm connected to said link; a throw-off arm upon which said controlling arm is pivoted; an actuator connected to one of said controlling-arm and link elements; a presser; and a link connecting 25 said presser to said throw-off arm whereby when the presser is raised to an inoperative position the needle is rendered inoperative on the work.
14. A stitch-forming mechanism of a sewing machine, including a needle-and-presser-mechanism which comprises the combination with a needle device of a link, as 20, attached to said needle device; an arm, as 26, attached to said link and extending transversely thereof; means for supporting said arm and moving it longitudinally; an actuator, as 18, connected to one of said arm and link elements; a presser; and a connection between said 30 presser and said arm-supporting and moving means whereby when the presser is raised to an inoperative position the needle is rendered inoperative on the work.
15. A stitch-forming mechanism of a sewing machine, including a needle-and-presser-mechanism which comprises the combination with a needle slide of a link, as 20, attached to the needle slide; a controlling arm or link, as 26; an adjustable 40 arm, as 25, to which said controlling arm is pivoted; an actuating arm or crank, as 18; a link, as 19, for driving said controlling arm, said link 20, and said needle slide; said link 19 being connected to said crank 45 18; and a presser connected by a link to one of said elements 25 and 26 whereby when the presser is raised to an inoperative position the needle is rendered inoperative on the work.
16. A stitch-forming mechanism of a sewing machine, including a needle-and-presser-mechanism which comprises the combination with a needle slide of a link motion, one member whereof, consisting of 50 55 60 65 70 75 80 85 90 95 100 105 110 115 120 125 a driving arm or crank, is journaled in the framework, and another member whereof, consisting of an adjustable arm or crank, is also pivoted upon the framework and provided with a finger-piece; said link motion being so organized that by a movement of said finger-piece the stroke transmitted through said link motion to said needle slide may be altered; stops for said adjustable arm or crank; a presser; a spring for said presser; and means connecting said presser to said adjustable arm or crank; said spring holding the latter against one of said stops when the presser is lifted.
17. In a sewing machine mechanism, the combination with a presser foot slide having a slideway, a needle slide mounted in said slideway, a system of linkage for reciprocating the needle slide, means for raising the presser foot slide and adjusting the throw of the linkage, and a connection between the presser foot slide and said means whereby the motion of the presser foot due to the rise and fall of the feed dog will be ineffective upon the linkage.
18. A stitch-forming mechanism of a sewing machine, including a needle-and-presser-mechanism which comprises the combination with a needle device and means for actuating the same, of a variable connector between said needle device and said actuating means; an arm or crank, as 25, connected to said variable connector; a stop, as 38, for said arm 25; a presser connected to said arm 25; and a spring, as 35, for said presser; said spring operating, when the presser is thrown up, to hold said arm against said stop.
19. A stitch-forming mechanism of a sewing machine, including a needle-and-presser-mechanism which comprises the combination with a needle device and means for actuating the same, of a variable connector between said needle device and said actuating means; an arm or crank controlling said variable connector; stops, as 37 and 38, for said arm or crank; a link, as 27, connected to said arm or crank; a presser connected to said link; and a spring for said presser; the movement of said arm raising said presser and compressing said spring, and the link swinging over the dead center at its point of connection to said arm, so that said spring detains said arm in the throw-off position and against said stop 38.
20. In a sewing machine mechanism, the combination with a presser foot slide having a guideway, a needle slide mounted in said guideway, a rock arm, a pair of links pivoted together and pivoted to said rock arm and needle slide and effective when in a substantially straight position and the rock arm in its lowest position, a rock arm,

a link connecting said rock arm and the
said pair of links for holding them either in
a substantially straight line or out of the
same for regulating the throw of said
needle slide, a linkage connecting said slide
and said latter rock arm and having free-
dom of movement for permitting independ-

ent motion of the presser foot incident to
the rise and fall of the feed dog.
